US0D1067524S

(12) **United States Design Patent** (10) **Patent No.:** **US D1,067,524 S**
(45) **Date of Patent:** **** Mar. 18, 2025**

(54) **WIG RACK**

(71) Applicant: **Qingdao Fumingweiye Trading Co., Ltd.**, Shandong (CN)

(72) Inventor: **Yuping Wang**, Shandong (CN)

(73) Assignee: **Qingdao Fumingweiye Trading Co., Ltd.**, Shandong (CN)

(**) Term: **15 Years**

(21) Appl. No.: **29/892,557**

(22) Filed: **May 18, 2023**

(51) LOC (15) Cl. **28-04**

(52) U.S. Cl.

USPC **D28/93**
